DRINKING VESSEL WITH ANIMATED DISPLAY

Daniel Rosenthal, Brooklyn, N. Y.

Application September 8, 1948, Serial No. 48,300

5 Claims. (Cl. 46—118)

1

This invention relates to drinking vessels and more particularly to instrumentalities for providing an animated display in conjunction with and visible through the bottom of a drinking vessel.

It has heretofore been proposed to display various advertising and other objects through the bases of glass tumblers, cups, bowls and other vessels intended to be held in the hand and having transparent bases. In most instances these objects have been fixed. Some have been free to move, but without any control over that movement. Thus in neither the fixed nor the movable form would the object necessarily appear upright to the user, regardless of the position in which the vessel was held for use.

The presence of a figure, in conjunction with the base of a drinking vessel, which figure will always be upright and will show some animation in response to movement of the vessel, has a definite value in no way touched upon by the incomplete attempts of the prior art.

Besides being generally attractive as a display, it is valuable for a number of specific purposes. Some of these are advertising, education and the enticement of children to drink commodities which they might otherwise avoid. The display can be made up in various series whether the holders therefor be part of the vessel or be interchangeable elements. Thus such things as a line of commodities to be advertised, a variety of mechanical movements, animals, birds, or nursery rhyme characters can be displayed. All of these, in accordance with the invention, will stand upright as viewed by the holder of the vessel, and will have some parts thereof movable with respect to the other parts.

It is, accordingly, the principal object of my invention to provide animated displays to be viewed through the bases of drinking vessels.

Another object is to provide such displays which have one part movable with respect to the body of the member on which they are mounted and have other parts movable with respect to the first part.

Other objects of the invention are to provide such displays which may be furnished in a series for inter-changeable use and which, whether singly, or in a series, will be entirely protected from contact with any of the beverage, and, finally, to provide such displays in an economical and effective manner.

Further objects of the invention will appear as a description of the embodiments thereof, taken in conjunction with the accompanying drawing proceeds. In that drawing:

2

Figure 1 is an elevation of a drinking vessel in accordance with the invention, with a fragment of that vessel broken away in section.

Figure 2 is a plan view taken on line 2—2 thereof.

Figure 3 is a vertical section taken on line 3—3 of Figure 2.

Figure 4 is a view similar to Figure 2, but showing a slightly modified form of the invention.

Figure 5 is a vertical section taken on line 5—5 of Figure 4.

Figure 6 is a view similar to Figure 2, showing another modification of the invention.

Figure 7 is a vertical section taken on line 7—7 of Figure 6, and

Figure 8 is a detailed sectional view of a form of pivot employed in conjunction with the invention.

Though in the drawing just referred to, and in the detailed description thereof to follow, the display device of the invention, as shown and described, is applied to a drinking glass, it is, of course, to be understood that such is only for illustrative purposes. The receptacle might, of course, be any food product or beverage containing vessel of a transparent nature, such as, but without limitation to, soup bowls, cereal bowls, glass cups or mugs, as well as drinking glasses or tumblers. Furthermore, though the display objects illustrated are such as would appeal to children, it is to be understood that advertising displays, or any other figure capable of animation could be employed.

In Figure 1, the drinking glass, or tumbler, shown at 1 may be of any ordinary type, and be formed of glass, or a plastic, the only compelling requirement being that its bottom be transparent. A base 2 is shown as applied to the bottom of the tumbler 1 as a separate element as indicated by the line of separation 3. The base 2 may be per-

manently affixed to the tumbler if desired. When, however, it is desired to vary the displays to be seen through the bottom of a tumbler, the base 2 would be made as a separate element, as shown in Figures 2 through 7. In such figures,

the base 2 is depicted as having a supporting bottom 4 surrounded by an upstanding side wall 5, which side wall is inset around its upper end at 6 in order to provide a ledge for the reception of the bottom end of the tumbler.

In the form shown in Figures 2, 3 and 8, the bottom 4 has a flat upper surface 7, above which is suitably mounted the support member 8 of a suitable display element. This support member is preferably pivotally mounted in suitable manner with respect to the bottom 4. Here such

mounting is accomplished by the use of a suitable post 9, the lower end of which is secured in the base 4. The other end is reduced at 10 to provide a shoulder 11 to serve as a pivotal mounting for the member 8. The member 8 is suitably held thereon by some means such as the cap screw 12 (Figure 8).

The member 8 has supplemental portions 13 and 14 pivotally mounted on and above it, by means of pivot pins 15 and 16. In addition, the supplemental portion 14, here given the appearance of a cow, is provided with extremities such as 17, 18, 19 and 20. These latter are suitably pivoted to the portion 14, as shown at 21 and 22.

In order to properly portray the idea of the cow, 14, jumping over the moon 13, as is done in Figure 2, it is, of course, necessary for the moon to take the lower position of the two figures no matter in what position the glass be held for drinking therefrom, or viewing through the bottom thereof. This is accomplished by suitably counter-weighting the proper portion of the display element. Here such is shown as being accomplished by making the moon substantially heavier than the other figure. This will cause the support member 8 to move on its pivot 10 and adopt the desired position. Similarly, the individual figures 13 and 14 themselves have their pivots 15 and 16 so placed with respect to their centers of gravity, that they will adopt an upright position. The legs 17, 18, 19 and 20, of the cow are mounted to swing rather freely, but, in the course of their swinging, will seek to fall into a normal downward position. In any event, the glass will probably not be held too steady, and the various elements of the display, being freely movable on their pivots, will display considerable animation in response to even slight movement of the glass.

A small bell 23 is hung around the neck of the cow depicted at 14. This bell is free to swing clear of the adjacent elements and, so long as the animation of the figure is substantial, the bell will ring sufficiently to be audible.

A different manner of providing animation is shown in Figures 4 and 5. Here, the display element is in the form of a jack-in-the-box, having a body 24, pivotally mounted at 26 on the pin 25, which, in turn, has its other end received in the portion 4. Its extremities, that is, the head 27, hands 28 and 29, and feet 30 and 31, are all suitably secured to the body 24 by spring elements 32, 33, 34, 35 and 36, respectively. These springs are so chosen that any movement of the display device, or of the glass to which it is applied, will serve to impart a jiggling movement to the aforesaid extremities. The whole construction is counter-weighted to make it stand upright by a counterweighting of the feet 31 and 30. As an alternative, of course, this could be accomplished by appropriately weighting the body instead. Finally, this figure carries in the hand 28 a stick 37 from which a bell 38 is suspended by means of a cord 39. The relationship of these parts is such that the bell 38 will be free to swing in response to the same sort of movement which causes movement of the feet, hands, etc., and will thus produce a tinkling sound to add to the attractiveness of the device.

In the modification shown in Figures 6 and 7, the bottom 4 is provided with an upper surface, the larger part of which, 40, is in the form of an inclined annulus extending downwardly from the side wall 5. A center portion 41 of the upper surface is retained in the flat form, but may be

dispensed with if desired, in which case the inclined annulus would extend right down to the center of the bottom 4. The figure shown in this embodiment is in the form of a jumping jack, whose arms and legs are designed to move up and down, in response to movement of the glass, or tumbler. This figure has a main body portion 42, pivotally mounted on the base 4 by means of a pivot pin 43. The arms 44 and 45, and the legs 46 and 47, are pivotally mounted on the body 42 at appropriate positions by means of suitable pivot pins 48, 49, 50 and 51.

The movement of these arms and legs, and the upright position of the figure, is provided for by a counterweight 52 which rides on the incline 40. A string, or wire, 53 connects the counter-weight 52 through branch strings with the portions of the arms and legs extending inward beyond their pivots. Thus, as the weight falls from the position shown in Figure 6 towards the side wall 5, the figure as a whole will first adopt an upright position from the point of view of the observer, and will thereafter raise its arms and legs. This action, however, is controlled by the presence of the incline 40, so as not to take place too abruptly. Furthermore, the incline 40 will serve to return the counter-weight 52 to a neutral position when the glass is moved from one position to another. The substantial movement of the arms and legs up and down can be readily achieved.

From the foregoing it will be apparent that bases for tumblers can be devised by following the teachings of my invention providing whatever movement it is desired to simulate. For instance, a series of nursery rhyme characters, or other attractive figures, could be provided, either in separate bases, or in bases already affixed to bottoms of glasses. If other age groups and types of the public are to be appealed to, whether by means of advertising or mere entertainment, other portrayals can be provided, whether in series or not. Also, as already pointed out, the bases, whether separate, or affixed to particular vessels, can be supplied for a great variety of vessels, so long as the same are transparent or at least have transparent bottoms.

Since certain changes may be made in the above described illustrations, and different embodiments of the invention could be made without departing from the scope thereof, it is intended that all matter contained in the above description, or shown in the accompanying drawing, shall be interpreted as illustrative, and not in a limiting sense.

Having described my invention, what I claim as new and desire to secure by Letters Patent is:

1. In a display construction for a vessel having a transparent bottom wherein a generally cup shaped member is formed with a portion to receive the base of said vessel and has a portion extending below the said receiving portion for the mounting of a display figure, said cup shaped member having a bottom, an upstanding side wall, therearound forming a chamber therewithin overlying said bottom, a display figure, a bell type sounding member forming part of said figure and connected to the main part of said figure by a flexible connector, means for mounting said display figure for pivotal movement in spaced relation to said bottom, said mounting means including a pivot pin extending from said bottom and engaged with said display figure, and means forming part of the visible portion of said figure.

to counterweight said figure to maintain the same in upright position.

2. In a display construction for a vessel having a transparent bottom wherein a generally cup shaped member is formed with a portion to receive the base of said vessel and has a portion extending below the said receiving portion for the mounting of a display figure, said cup shaped member having a bottom and an upstanding side wall therearound forming a chamber overlying said bottom, a display figure, fixed pivotal mounting means extending from said bottom and engaging said display figure for mounting the same in spaced pivotal relation with respect to said bottom, said display figure having a body portion and an auxiliary portion and connecting means for connecting said auxiliary portion with respect to said body portion for limited movement with respect thereto.

3. In a display construction for a vessel having a transparent bottom wherein a generally cup shaped member is formed with a portion to receive the base of said vessel and has a portion extending below the said receiving portion for the mounting of a display figure, said cup shaped member having a bottom and an upstanding side wall therearound forming a chamber overlying said bottom, a display figure, pivotal mounting means extending from said bottom and engaging said display figure for mounting the same in spaced relation with respect to said bottom, said display figure having a body portion and an auxiliary portion, and flexible connecting means for connecting said auxiliary portion with respect to said body portion for limited movement with respect thereto.

4. In a display construction for a vessel having a transparent bottom wherein a generally cup shaped member is formed with a portion to receive the base of said vessel and has a portion extending below the said receiving portion for the mounting of a display figure, said cup shaped member being formed with a bottom and an upstanding side wall therearound and including a

chamber within said cup shaped portion beneath the receiving portion for the base of the vessel, a single display figure seated in said chamber, means for mounting said display figure on said bottom for pivotal movement with respect thereto, and means forming parts of said figure, but located at separate extremities thereof, to counterweight said figure to maintain the same in upright position.

5. In a display construction for a vessel having a transparent bottom wherein a generally cup shaped member is formed with a portion to receive the base of said vessel and has a portion extending below the said receiving portion for the mounting of a display figure, said cup shaped member having a bottom and an upstanding side wall therearound forming a chamber overlying said bottom, a display figure, fixed pivotal mounting means extending from said bottom and engaging said display figure for mounting the same in spaced pivotal relation with respect to said bottom, said display figure having a body portion and an auxiliary portion and a light weight helical spring for connecting said auxiliary portion with respect to said body portion for limited movement with respect thereto.
